UNITED STATES PATENT OFFICE

MAX LORENZ, OF STUTTGART, GERMANY, ASSIGNOR TO ROBERT BOSCH AKTIENGESELLSCHAFT, OF STUTTGART, GERMANY

CARBURETOR

Application filed August 11, 1930, Serial No. 474,522, and in Germany September 2, 1929.

The present invention relates to spray carburetors of the type having an air throttle and a float chamber in which the air space of the float chamber is connected to one choke tube by an air duct so that a vacuum is maintained in said air space to draw fuel from the tank into the float chamber, whilst the fuel space of the float chamber is connected to a second or third auxiliary choke tube in which a higher vacuum obtains than in the first choke tube. When the air throttle of this carburetor is closed such a high vacuum is produced in the mixing chamber that the fuel in the float chamber begins to vaporize vigorously whereby the vacuum in the air space of the float chamber is reduced and the fuel can escape from the nozzle of the main fuel pipe. This fuel collects in the mixing chamber and under the circumstances vapors sucked from the air space of the float chamber can also be deposited therein. As a result when the air throttle is subsequently opened the mixture is much too rich and the consumption of fuel is unnecessarily great.

According to the present invention, the mixing chamber is also closed from the engine by a throttle to such an extent when the air throttle is closed that the vacuum arising in the mixing chamber only reaches a degree necessary for keeping the fuel level at the required height in the float chamber, therefore to suck the fuel with certainty from the supply tank.

One form of construction according to the invention is shown by way of example in the accompanying drawing.

A mixing tube *a* has a main choke tube *b* in which is disposed an auxiliary choke tube *c*. The throat of the choke tube *b* is connected to the air space of the float chamber *e* by a passage *d*. A pipe *f* having a constriction *g* leads from the fuel space of this float chamber to the throat of the choke tube *c*. The air throttle valve *h* is connected to a second throttle valve *k* behind or in rear of the choke tubes by a rod *i*. This throttle *k* has a slot *m* formed therein from which projects the end of a pipe *n* having a constriction *o* for light running when the throt-

tle is closed. Primary air for light running is supplied through an orifice *p*.

When the air throttle *h* is closed, the throttle *k* is also positively closed. A high vacuum is then produced by the light running motor in the chamber behind the throttle *k* i. e. on the side of the throttle nearest the engine. This vacuum however cannot act so strongly in the mixing chamber that the fuel in the float chamber is excessively vaporized and can thereby flow out of the main pipe *f* through the reduction of the vacuum taking place in the air space of the float chamber. The degree of vacuum in the mixing chamber is determined by the free cross-section of the connection between the mixing chamber and the chamber behind the throttle *k* and in addition by the cross-section of the opening *p*.

The arrangement for light running can also be constructed in the manner usual in the normal carburetors in which air is sucked out of the mixing chamber through the mouth of the pipe *n* through a groove on the throttle valve *k* or by partly opening the throttle valve.

What I claim is:—

1. A self-feeding carburetor comprising a casing which includes a mixing chamber, at least two choke tubes adapted to produce different degrees of vacuum for any given degree of engine suction, a float chamber the air space of which is connected to the choke tube of lower vacuum and the fuel space to the choke tube of higher vacuum, an air throttle in advance of said choke tubes and a mixture throttle in rear of said choke tubes, the mixture throttle being operatively connected to said air throttle so that when the air throttle is closed, the passage from the mixing chamber to the engine is partly open but is sufficiently closed to prevent the vacuum in the mixing chamber from appreciably exceeding that required to maintain the fuel level in the float chamber.

2. A self-feeding carburetor comprising a casing which includes a mixing chamber and having an opening to atmosphere adjacent the engine end of said mixing chamber, at least two choke tubes adapted to produce dif-

ferent degrees of vacuum for any given degree of engine suction, a float chamber the air space of which is connected to the choke tube of lower vacuum and the fuel space to the 5 choke tube of higher vacuum, an air throttle in advance of said choke tubes, a mixture throttle having an opening formed therein located in rear of said choke tubes and associated with said air throttle and an auxiliary fuel 10 supply duct for slow running purposes leading from the float chamber to said opening in the mixture throttle.

3. A self-feeding carburetor comprising a casing which includes a mixing chamber, at 15 least two choke tubes adapted to produce different degrees of vacuum for any given degree of engine suction, a float chamber the air space of which is connected to the choke tube of lower vacuum and the fuel space to the 20 choke tube of higher vacuum, an air throttle in advance of said choke tubes, a mixture throttle having an opening formed therein located in rear of said choke tubes and being operatively connected to said air throttle, an 25 auxiliary fuel supply duct for slow running purposes leading from the float chamber to said opening in the mixture throttle, and an air orifice directly connecting the mixing tube to the atmosphere in advance of said mixture 30 throttle for supplying air for light running and for fixing the vacuum in said mixing tube.

In testimony whereof I have hereunto affixed my signature.

MAX LORENZ.
